199,891

TRANSPARENT MITT FOR SERVING CAKE

Gladys L. Hay, 2709 26th St., Lubbock, Tex.

Filed Nov. 15, 1962, Ser. No. 72,507

Term of patent 14 years

(Cl. D3—11)

FIG. 1 is an elevational view of the back of a transparent mitt for serving cake, the palm side thereof being similar in appearance except for the omission of the bow and spray of flowers; and

FIG. 2 is a side elevational view thereof.

I claim:

The ornamental design for a transparent mitt for serving cake, as shown and described.

References Cited by the Examiner

Handbag and Accessories for January 1957, page 34, glove shown with embroidered floral design 2nd from right in square 2nd from bottom.

Handbag and Accessories for April 1957, Nylon glove at top right of page 17.

Premium Practice January 1951, p. 114, "Beauty Mitts" by Forecast Plastic Premium.

Sears, Roebuck & Co. Catalog No. 219, Chicago F&W, 1959, page 450 item Z glove.

EDWIN H. HUNTER, Primary Examiner.